UNITED STATES PATENT OFFICE.

ERNEST C. LAWTON, OF MOHAWK, NEW YORK.

KNOCKDOWN BOOKCASE.

1,216,465.

Specification of Letters Patent. Patented Feb. 20, 1917.

Application filed June 1, 1912. Serial No. 700,935.

To all whom it may concern:

Be it known that I, ERNEST C. LAWTON, a citizen of the United States, residing at Mohawk, in the county of Herkimer and State of New York, have invented certain new and useful Improvements in Knockdown Bookcases, of which the following is a specification.

This invention relates to an improvement 10 in knock down sectional book cases and the object is to provide means for fastening the several sections together as they are stacked and keeping them alined.

The invention consists of certain novel features of construction and combinations of parts which will be hereinafter more fully described, illustrated and claimed.

In the accompanying drawings:

Figure 1 is a perspective view of a base, 20 book section and top to show the manner of assemblage;

Fig. 2 is an enlarged detail sectional view showing the manner of connecting an end of the book section to the base or bottom of the 25 book section;

Fig. 3 is a bottom plan view of one end of a book section;

Fig. 4 is a top plan view of one end of a book section;

Fig. 5 is a detail perspective view showing 30 the manner of mounting the pins in the ends of the book section.

A book section is disclosed in Fig. 1 which consists of ends 1, a shelf or bottom 2 and 35 back 3. Several sectional members are assembled in the manner shown, the end sections being provided along their lower edges with the grooves 4 and tenons 5 for forming a dovetail connection and the shelf or bottom

40 2 being provided with grooves 6 and tenons 7, the tenons 7 of the shelf being received in the grooves 4 of the end members, and the tenons 5 of the end members being received in the grooves 6 of the shelf member. The second tenon from each side of the shelf member is omitted, thus leaving one of the 45 grooves of the end member open and forming a cavity C for the reception of a key or pin 9 carried by the upper edge of the end member 1 of the section below. The end members 1 are provided with dovetail sock-

ets in their upper edge in which the dovetailed or keystone shaped pins 9 are received. These pins are adapted to pass into the cavity C of the adjacent shelf member 2 of the 55 book section, and as shown in Fig. 1 the top member B is provided with openings 10 for the reception of the pins 9 for fastening the top section to the book section. The base section D, is also provided with pins 9 which 60 enter the cavities C of the book section for fastening the book section to the base.

From the foregoing it will be seen that I have provided a very simple means of fastening several book sections together and 65 mounting the book sections upon the base member and for mounting the top member upon the book sections whereby the several book sections, top and base will be firmly held together, an enlargement or cavity being 70 formed of greater size than the usual dovetailed grooves which are formed in the shelf members by removing one of the tenons which forms a passage or cavity in the shelf members through which a pin or tenon can 75 be inserted into the vacant grooves of the end sections which are left open by the removal of the second tenons from each side of the shelf member or section.

Having thus described my invention, what 80 I claim as new and desire to secure by Letters Patent is—

1. In a knock-down bookcase, the combination of base, top and book sections, each book section consisting of end, back, and 85 shelf members, the end and shelf members provided with grooves and tenons, the tenons of the end member adapted to fit the ends of the shelf member, and the tenons of the shelf member adapted to fit the grooves of the end 90 members, one of said members having a tenon omitted therefrom, thereby forming a cavity by the groove of the other member and the space formed by omitting said tenon, and a pin carried by the end member of an 95 adjacent section adapted to enter said cavity for holding the sections together.

2. A knock down book section comprising a shelf, and end members having grooves and tenons formed thereon, and positioned 100 to interlock for holding the shelf and end members assembled, a tenon at each end of

the shelf member being removed for forming a cavity, said end members having sockets formed therein, and pins received in the sockets adapted to enter the cavities of the adjacent section for holding the two sections alined and fastening the end members together.

In testimony whereof I affix my signature, in the presence of two witnesses.

ERNEST C. LAWTON.
